(57) **CLAIM**

The ornamental design for a light fixture, as shown and described.

DESCRIPTION

FIG. 1 is a perspective view of a light fixture in accordance with my design;

FIG. 2 is a top plan view of the light fixture in accordance with my design along the line 2—2 in FIG. 1;

FIG. 3 is a bottom plan view of the light fixture in accordance with my design;

FIG. 4 is a front elevation view of the light fixture in accordance with my design;

FIG. 5 is a back elevation view of the light fixture in accordance with my design;

FIG. 6 is a side elevation view of the light fixture in accordance with my design; and,

FIG. 7 is an opposite side elevation view of the light fixture in accordance with my design.

The portions of the light fixture shown broken away in FIGS. 1-7 are to depict indeterminate length.

The broken-line disclosure of elements is understood to represent portions of the article in which the design is embodied, but which form no part of the claimed design.

Features of the design include the shape and configuration of the article and the pattern and ornament applied to the article as shown in the draftsman's representations.
